UNITED STATES PATENT OFFICE

115,214

DESIGN FOR A COMB

Charlie A. Moore, Nashville, Tenn., assignor of one-half to James A. Foster, Nashville, Tenn.

Application April 19, 1939, Serial No. 84,394

Term of patent 7 years

To all whom it may concern:

Be it known that I, Charlie A. Moore, a citizen of the United States, residing at Nashville, in the county of Davidson and State of Tennessee, have invented a new, original, and ornamental Design for a Comb, of which the following is a specification, reference being had to the accompanying drawing, forming part thereof.

I claim:—

The ornamental design for a comb, as shown.

CHARLIE A. MOORE.
